UNITED STATES PATENT OFFICE.

FRANK J. SIBOL, OF PERTH AMBOY, NEW JERSEY, ASSIGNOR TO RARITAN COPPER WORKS, A CORPORATION OF NEW JERSEY.

APPARATUS TO FACILITATE THE REMOVAL OF STARTING-SHEET DEPOSITS FROM THEIR RECEIVING BLANKS.

Application filed April 1, 1922. Serial No. 548,668.

To all whom it may concern:

Be it known that I, FRANK J. SIBOL, a citizen of the United States, and a resident of Perth Amboy, county of Middlesex, and 5 State of New Jersey, have invented certain new and useful Improvements in Apparatus to Facilitate the Removal of Starting-Sheet Deposits from Their Receiving Blanks, of which the following is a specification.

10 This invention relates to apparatus for handling and manipulating the blanks which have received deposits of metal, said deposits to be used to form the starting plates or cathodes for electrolytic refining apparatus.

15 More particularly, it relates to an apparatus to facilitate and make easy the removal of the thin deposits of metal formed on a forming or stripping blank to serve as a starting sheet or base of the cathode for electrolytic 20 refining.

The cathode base or starting sheet or plate for electrolytic refining is formed by the electrolytic deposition on a cathode plate made of lead or copper and commonly known 25 as a stripping blank. At intervals the stripping blanks are removed from the electroplating bath and the thin deposit of copper is stripped off to form the starting plate or cathode base for electrolytic refining. In 30 forming copper cathode bases it is necessary to apply oil or other like parting material to the stripping base before forming the electrolytic deposits so that the deposits may be readily separated and removed from the base. The parting material is applied to the 35 plate while hot and the electro-deposition takes place in a hot bath so that an even and firm deposit may be formed. After the deposit is stripped from the stripping base, it 40 is provided with loops or other supporting means for suspension in a refining tank.

The stripping blanks are quite heavy and also being hot and covered with acid, are very difficult to handle, and in handling, are 45 frequently injured. Even when cranes are employed in lifting the plates, the work is slow, laborious and expensive. These difficulties are largely avoided by the present invention, one object of which is to provide 50 an apparatus which will permit a number of blanks to be removed from a bath and conveniently handled for stripping the deposit of copper.

Another object of the invention is to provide an apparatus in which a number of 55 stripping plates may be received and each plate may be independently brought to a position of free and ready access for stripping its deposit of copper.

With these and other objects in view, the 60 invention comprises the apparatus illustrated in the drawings and described in the following specification and claims.

The various features of the invention are illustrated in the accompanying drawings, 65 in which:

Fig. 1 is a plan view of an apparatus for receiving and handling blanks embodying a preferred form of the invention.

Fig. 2 is an end elevation of the apparatus 70 illustrated in Fig. 1, and

Fig. 3 is a side elevation of the apparatus illustrated in Figs. 1 and 2, the position of a blank ready for stripping being shown in 75 dotted lines.

In the present invention the stripping blanks removed from the electroplating bath for stripping are received and suspended on narrow, upright carriages mounted on parallel, spaced tracks. When these carriages 80 are positioned at one end of the tracks a number of blanks may be carried from the bath by a crane and deposited in a group on the carriages. Each carriage with its blank may then be moved independently forward on its track to clear it from the others so that both sides are exposed for 85 stripping, a platform being arranged at each side of the tracks to permit the blanks to be conveniently reached. The carriages are

preferably formed of a frame having a front and a rear upright, on the upper ends of which, notches are provided in which the ends of a supporting rod of the blank may be supported so that the blank may hang 90 downwardly between the uprights. Suitable wheels or rollers are provided at the bottom of the frame to run on their respective tracks. A number of guides are also positioned 95 above, and parallel with the tracks to hold the carriages and blanks in their proper position on the tracks.

Referring more particularly to the accompanying drawings, stripping blanks 10 carried from the plating tanks by an electric 105 crane or other means are received on car-

riages 12 arranged in a parallel relation on tracks 14. The carriages are so arranged that a number of blanks may be placed on carriages at one time or blanks may be deposited on the carriages and left there until a time convenient for the stripping operation. When the copper deposit is to be stripped from a blank the carriage holding the blank is moved forwardly on the track, 5 between guide rails 16, until it has moved clear of the other plates. In this forward position both sides of the blank are exposed and the deposit may be removed by workmen on platforms 18 and 20 or on the rails 10 16 in case one of the central carriages is being used. When the deposits have been removed from the blank, the carriage is returned to its original position and another blank and carriage is advanced for the removal of its deposit.

The carriages 12 are formed of a forward upright 22 and a rear upright 24 joined at their lower part by horizontal bars or beams 25 and 28 and cross beams 30 and 32 to 20 form a rigid frame. The carriage is supported by wheels 34 and 36 on which the lower beam 26 rests and which are adapted to roll on the track 14. At the upper ends of the uprights, brackets 38 and 40 are 30 mounted, the upper edges of which are notched to receive the ends of a supporting cross bar 42 for the blank 10 and by which the blank is suspended. Notches 44 are also provided in the upper edges of the blanks 35 through which hooks 46 of a crane or other conveying device may be inserted when the blank is being placed on the carriage or removed therefrom.

The uprights 22 and 24 may be formed 40 in any suitable way, the union of two angle irons 48 and 50 illustrated in the drawings forming a very desirable construction because of its strength and lightness. The cross beams 30, 32, 26 and 28 may also be 45 formed of angle iron and joined to the uprights by gusset plates 52, inserted between the angle irons 48 and 50.

Through the above described invention the stripping blanks may be easily and 50 quickly handled without the necessity of the workman lifting or otherwise moving the blanks from the carriages on which they are deposited from the plating baths.

Having thus described my invention, 55 what I claim as new and desire to secure by Letters Patent is:

1. An apparatus of the kind described which comprises a track, closely spaced guides lengthwise of said track, a carriage 60 mounted on said track and adapted to move between said guides, said carriage having front and rear uprights and means on said uprights adapted to receive and support the cross bar of a stripping blank.

2. An apparatus of the kind described

which comprises a track, closely spaced guides lengthwise of said track, a carriage mounted on said track and adapted to move between said guides, said carriage having front and rear uprights, means on 70 said uprights adapted to receive and support the cross bar of a stripping blank and a platform adjacent said guides.

3. Apparatus of the kind described which comprises a series of parallel tracks, 75 a series of closely spaced guides positioned lengthwise of said tracks, a series of carriages mounted on said tracks and guided in spaced relation to each other lengthwise of said tracks and means on each of said carriages adapted to independently support a stripping blank.

4. Apparatus of the kind described which comprises a series of parallel tracks, 80 a series of closely spaced guides positioned lengthwise of said tracks, a series of carriages mounted on said tracks and guided in spaced relation to each other lengthwise of said track, means on each of said carriages adapted to independently support a stripping blank and a platform adjacent said 85 tracks and guides.

5. Apparatus of the kind described which comprises a series of closely spaced 90 tracks, narrow upright carriages mounted on said tracks for independent movement, said carriages having forward and rear uprights and means on said uprights for mounting a stripping blank, said carriages being adapted to be positioned to receive a 95 number of spaced blanks and to be singly advanced to bring each blank into a separate position from the others.

6. Apparatus of the kind described which comprises a series of closely spaced 100 tracks, narrow carriages mounted on said tracks, said carriages comprising a front and a rear upright, a connecting structure at the lower ends of said uprights and roller 105 wheels supporting said carriages, and means on the upper ends of said uprights for supporting a stripping blank between the upper part of said front and rear uprights.

7. Apparatus of the kind described which comprises means for supporting 110 stripping blanks in substantially parallel, spaced relation and means for permitting said supporting means and blanks to be individually moved laterally in the plane of the moved blank out of position between its adjacent blanks.

8. Apparatus of the kind described which comprises means for suspending 115 stripping blanks from their upper edges in spaced relation and means for permitting a blank to be moved edgewise radially in its suspended relation to a position clear of its adjacent blanks.

9. Apparatus of the kind described which comprises means for supporting a 120

stripping blank edgewise, and means for permitting said supporting means and blank to be moved laterally in the plane of the blank.

- 5 10. Apparatus of the kind described which comprises means for supporting a stripping blank edgewise, and means for

enabling a supported blank to be moved laterally in the plane of said blank.

In witness whereof, I have hereunto set 10 my hand at Perth Amboy, county of Middlesex State of New Jersey, this 28th day of March, 1922.

FRANK J. SIBOL.
